AUTOMATIC NIGHT LIGHT

Wayne A. Smith, Fort Worth, Tex.

Application August 30, 1955, Serial No. 531,347

4 Claims. (Cl. 315—93)

This invention relates to lighting systems wherein continuous operation is maintained in the event of failure of a main bulb or electrical unit or when the main power supply is interrupted.

Night lights are widely used in commercial establishments to discourage theft and to display merchandise through the night. Failure of a night light may enable burglars to enter an establishment unobserved. Aside from the fact that light bulbs have a limited life, power failures due to blown fuses or transmission difficulties result in periods when normal means of illumination are not available and theft is thereby encouraged. In addition to normal commercial applications there are a number of uses where continuous operation of light bulbs or other appliances is of great importance; among these special uses for continuous operation are airport runway illuminators, electric lights used for heating purposes in brooder houses and operation of electrical appliances.

An object of the invention is to provide an electrical circuit for illuminating devices wherein a reserve bulb is automatically turned on in the event that a regularly used bulb should fail.

Another object of the invention is to provide an illuminating device which automatically substitutes battery operated illuminating means when power failures eliminate a normal source of line current.

Another object of the invention is to provide a reliable means of illumination which may be actuated by either manual or clock controlled means.

Another object of the invention is to provide means wherein the clock controlled operation of a reliable illuminating device may be utilized to connect and disconnect less important circuits, such as lighted sign circuits with line current.

Another object of the invention is to provide an arrangement of components in a reliable illuminating source wherein widely separated bulbs, each provided with automatic substitution means, may be actuated from one clock controlled source.

A further object of the invention is to provide separate and independently operable batteries for each of a number of emergency sources of illumination wherein battery operation is supplied to each source as needed and yet all sources are controlled by the clock operation of a master unit.

These and other objects will become apparent from the following description and the accompanying drawing, wherein:

Figure 1 is a diagrammatic view of a master unit of the invention.

Figure 2 is a diagrammatic view of a subordinate unit of the invention.

In the drawing, one wire 11 of a current source is electrically connected to one armature 12 of a double pole double throw switch A. The upper or first contact point 13 of the armature 12 is wired electrically to one contact point 14 of a double pole single throw clock operated switch 15. Any of a number of commercially

2

available mechanical or electrical clock operated switches may be used, and if electrical, should be wired in parallel with power supply as indicated by the dotted lines 16 and 17 and with the circuits to be described. The armature 18 opposite the contact point 14 of the clock operated switch 15 is wired through a fuse 19 to one binding post of the actuating coil of a normally closed single pole single throw relay 20. One binding post of the actuating coil of a double pole double throw relay 21 is likewise wired through the fuse 19 to the same armature 18 of the clock operated switch 15. The other binding post of the actuating coil of the double pole double throw relay 21 is wired to one terminal of an electric light bulb 22; the same terminal of the electric light bulb 22 is wired to the armature 18 of the clock operated switch 15 through a resistor 23 and the fuse 19 successively. Another resistor 24 is wired in parallel with the first mentioned resistor 23 and in series with the light bulb 22 and is provided with a switch 25 at one of its terminals in series with the resistor 24. The other terminal of the light bulb 22 is wired through a switch 26 to the second wire 27 of the current source. The other binding post of the actuating coil of the single pole single throw relay 20 is wired to one armature 28, hereinafter referred to as the first armature, of the double pole double throw relay 21. The normally open contact point 29 of the first armature 28 of the double pole double throw relay 21 is wired to the first mentioned terminal of the electric light bulb 22. The normally closed contact point 30 of the first armature 28 of the double pole double throw relay 21 is wired to one terminal of a second light bulb 31. The same terminal of the second light bulb 31 is wired to the armature 18 of the clock operated switch 15 through a resistor 32 and the fuse 19 successively. Another resistor 33 is wired in parallel with the resistor 32 and in series with the light bulb 31 and is provided with a switch 34 at one of its terminals in series with the resistor 33. The other terminal of the second light bulb 31 is electrically connected to the normally closed contact point 35 of the second armature 36 of the double pole double throw relay 21. The second armature 36 of the double pole double throw relay 21 is wired through a switch 37 to the second wire 27 of the current source.

A battery 38 is wired from one of its terminals to the armature 39 of the single pole single throw relay 20. The normally closed contact point 40 of the single pole single throw relay is electrically connected to one terminal of a third electric light bulb 41. The other terminal of the third light bulb 41 is wired to the lower or second contact point 42 of the second armature 43 of the double pole double throw switch A. The second contact point 42 of the second armature 43 of the double pole double throw switch A is also wired to the contact point 44 of the second armature 45 of the clock operated switch 15. The second armature 45 of the clock operated switch 15 is wired to the upper or first contact point 46 of the second armature 43 of the double pole double throw switch A. The second armature 43 of the double pole double throw switch A is wired to the second terminal of the battery 38. The second or lower contact point 47 of the first armature 12 of the double pole double throw switch A is wired to the fuse 19. A push button switch 48 is connected between the second armature 43 of the double pole double throw switch A and the second contact point 42 of the armature 43.

Line current outlet lines 49 and 50 are electrically connected respectively to the second wire 27 of the current source and through a fuse 51 to the second contact point 47 of the first armature 12 of the double pole double throw switch A. Control current outlet lines 52 and 53 are connected respectively to the first terminal of the bat-

ter 38 and to the second contact point 42 of the second armature 43 of the double pole double throw switch A.

In operation of the master unit described, the circuit of the actuating coil of the double pole double throw relay 21 is connected to the first wire 11 of the line current through the clock operated switch 15 and the double pole double throw switch A, and that circuit is completed to the second wire 27 of the line current source through the filament of the first light bulb 22. As long as the filament of the first light bulb 22 is intact, current flows through the actuating coil of the double pole double relay 21 and the armatures thereof 28 and 36 are held against their normally open contact points. In their described actuated positions, one of these armatures 36 interrupts the circuit of the second light bulb 31 while the other armature 28 shunts line current from the coil circuit of the single pole single throw relay 20 through the filament of the first bulb 22 thereby energizing the single pole single throw relay 20 and actuating its armature 39. The armature 39 of the single pole single throw relay 20 interrupts the circuit of the battery operated third light bulb 41 when actuated. So long as the filament of the first bulb 22 is capable of conducting current and so long as line current is available therefor, the circuits of the other two bulbs 31 and 41 are interrupted by actuation of the relays 21 and 20 and only the first bulb 22 receives current for illumination. The first bulb 22 is connected with current from the first wire 11 of the line current source through a resistor 23, the resistance of which is properly calibrated to provide suitable division of current between the coils of the relays 20 and 21 and the first light bulb 22. An additional resistor 24 is wired in parallel with the first resistor 23 and is provided with a switch 25 by which it may be utilized optionally to maintain suitable current balance with the coils of the relays 20 and 21 if the use of a higher wattage bulb is desired. It will be apparent to those skilled in the art that additional resistors or a rheostat may be employed to accommodate a large variety of bulbs drawing various wattages.

In the event that the first light bulb 22 burns out, the coil of the double pole double throw relay 21 becomes deenergized since its circuit will be interrupted at the broken filament of the light bulb 22. In their inactivated or normal state, the armatures 36 and 28 of the double pole double throw relay 21 respectively complete the circuit of the second light bulb 31 and direct the coil circuit of the single pole single throw relay 20 through the filament of the second bulb 31. Current is then fed to the second bulb 31 through a resistor 32 quantitatively selected to maintain a suitable current balance between the coil of the single pole single throw relay 20 and the second bulb 31. While the electrical values of the resistors 23 and 32 differ, their functions are alike; the resistors 24 and 33 likewise have different electrical values but serve identical functions for their respective bulbs. As the second bulb 31 burns, the armature 39 of the single pole single throw relay 20 remains in its actuated position and interrupts the circuit of the battery operated third light 41. In the event that both the first and second bulbs 22 and 31 burn out or that the source of line current fails, the coil circuits of both relays 20 and 21 will be interrupted and the armatures thereof will assume their normal positions. With the single pole single throw relay 20 deenergized, the normal position of its armature completes the battery current circuit of the third light 41 and emergency illumination is thereby provided.

The wiring of the double pole double throw switch A is such that its armatures 12 and 43 serve as conductors of line and battery current respectively. The upper contact points 46 and 13 connect these current sources with a clock operated switch 15 while the lower contact points 42 and 47 serve to bypass the clock operated switch. Thus, the double pole double throw switch A may be used to operate the lights directly, to operate the lights

through a clock operated switch, or to turn the invention off by interrupting the current sources.

Switches 26 and 37 are provided between the light bulbs 22 and 31 respectively and the second wire 27 of the line current source so that the filament circuit of each bulb 22 and 31 may be artificially interrupted to test the working order of the invention. A push button type switch 48 is wired across the second armature 43 of the double pole double throw switch A and its second contact point 42 to provide a shunt circuit around the switch A for testing the strength of the battery and the working order of the battery operated light 41.

A line current outlet 49 and 50, subject to the operations of the clock operated switch 15 and the double pole double throw switch A, is provided for the operation of external lights and appliances electrically connected to the master unit of the invention or for the operation of subordinate units. A battery powered control current outlet 52 and 53 is provided for the emergency control of subordinate units.

The construction and circuitry of a subordinate unit (as illustrated in Figure 2) is, in many respects, identical with the construction and circuitry of the described master unit. Those skilled in the art will readily recognize the similarities and will see upon comparison of the two units that the principal differences reside in the absence of the main switches and placement of a second single pole single throw relay in the circuit of the battery operated light. In order to avoid repetitious description, identical components with identical functions are given like numbers in the two figures and are suffixed by the letter *a* in the diagram of the subordinate unit.

In the drawing with particular reference to the subordinate unit (Figure 2), line current source wires 11a and 27a are electrically connected to power line outlets 50 and 49 of the master unit. Lights 22a and 31a are wired to the line current source through identical components and in like manner to the lights 22 and 31 of the master unit. Control current inlet lines 54 and 55 are electrically connected to the control current outlet lines 52 and 53 of the master unit. One control current inlet line 54 is wired to a terminal of the actuating coil of a second single pole single throw relay 56. The other terminal of the actuating coil of the second single pole single throw relay 56 is wired to the armature 39a of the first single pole single throw relay 20a. The normally closed contact point 40a of the first single pole single throw relay 20a is wired to the other control current inlet wire 55. One terminal of a battery 38a is wired to the armature 57 of the second single pole single throw relay 56. The normally open contact point 58 of the second single pole single throw relay 56 is electrically connected to a terminal of the third bulb 41a. The second terminal of the third bulb 41a is wired to the second terminal of the battery 38a. A switch 59 is provided in one of the line current inlet wires.

In operation of the subordinate unit, the first and second bulbs 22a and 31a are operated by the relays as in the master unit. In the second single pole single throw relay 56, however, the dependence upon actuating current from the master unit prevents actuation of the third bulb 41a when the master unit is not turned on. The third bulb 41a is activated if the master unit is switched on and a power failure occurs or the first two bulbs 22a and 31a of the subordinate unit burn out. In the absence of line current, or with the switch A of the master unit in open position, or with switch A closed in the upper position and the clock operated switch 15 in open position, the third bulb 41 of the master unit and the third bulb 41a of the subordinate unit may be illuminated by closing the battery test push button 48 of the master unit.

The invention is not limited to the exemplary construction herein shown and described, but may be made in various ways within the scope of the appended claims.

What is claimed is:

1. A night light comprising a source of electrical current, an electric light bulb wired to said source of electrical current, a double pole double throw relay having its actuating coil wired in series with said electric light bulb, an electrical resistor wired in series with said electric light bulb and in parallel with the actuating coil of said relay, a second electric light bulb wired in parallel with the first said electric light bulb through an armature of said relay and the contact thereof, a second resistor wired in series with the second said electric light bulb, a second relay having its actuating coil wired in parallel with the first said resistor and in series with the first said electric light bulb through a second armature of the first said relay and a cold open contact point of the second said armature of the first said relay and wired in parallel with the second said resistor and in series with the second said electric light bulb through the second said armature of the first said relay and through the cold closed contact point of the second said armature, a battery and a third electric light bulb wired to said battery through the armature of the second said relay and through the cold closed contact point of the said armature of said second relay.

2. The invention as defined in claim 1 and wherein a third resistor and a manual switch are wired in series with one another and in parallel with the first said resistor and in series with the first said bulb, and a fourth resistor and a second manual switch wired in series with each other and in parallel with the second said resistor and in series with the second said bulb.

3. The invention as defined in claim 1 including a clock operated switch and alternative means to connect said source of electrical current and said battery to the said lights respectively associated therewith either directly or through said clock operated switch.

4. The invention as defined in claim 3 including a subordinate unit including a first plug wired to said source of electrical current in series through said clock

operated switch and said alternative means, and directly through said alternative means; a second plug wired to said battery in series through said clock operated switch and said alternative means, and directly through said alternative means, a fourth electric light bulb wired to the first said plug, a third relay having its actuating coil wired in series with the fourth said electric light bulb, a fifth electrical resistor wired to the first said plug in series with the fourth said electric light bulb and wired in parallel with the actuating coil of the third said relay, a fifth electric light bulb wired in parallel with the fourth said electric light bulb through an armature of the third said relay and through a cold closed contact point of said armature of the third said relay, a sixth electrical resistor wired in series with said fifth electric light bulb, a fourth relay having its actuating coil wired in parallel with the fifth said resistor and in series with the fourth said electric light bulb through a second armature of the third said relay and a cold open contact point of the second said armature of the third said relay and wired in parallel with the sixth said resistor and in series with the fifth said electric light bulb through said second armature of the third said relay and the cold closed contact point of said second armature of the third said relay, a second battery, a fifth relay having its actuating coil wired to the second said plug through the armature of the fourth said relay and through the cold closed contact point of the armature of the fourth said relay, and a sixth electric light bulb wired to the second said battery through the armature of the fifth said relay and through the cold open contact point of the armature of the fifth said relay.
